United States Patent Office

Des. 190,493
Patented June 6, 1961

190,493

DICTATING MACHINE

Peter Sieber, Frankfurt-Main-Seckbach, and Arnold Schürer, Offenbach-Main, Germany, assignors to Olympia Werke A.G., Wilhelmshaven, Germany

Filed Oct. 19, 1960, Ser. No. 62,542

Term of patent 14 years

(Cl. D26—5)

Fig. 1.

Fig. 2.

Fig. 3.

FIG. 1 is a perspective view as seen from the front, side and top of a dictating machine, showing our new design;

FIG. 2 is a perspective view as seen from the front and top; and

FIG. 3 is a perspective view as seen from the rear, opposite side and top thereof.

The essential features of the design reside in the portions shown in full lines on the drawing.

We claim:

The ornamental design for a dictating machine as shown and described.
